DESIGN FOR A BABY BUNTING

Esther Brande, Garden City, N. Y.

Application April 18, 1947, Serial No. 138,468

Term of patent 3½ years

(Cl. D92—2)

To all whom it may concern:

Be it known that I, Esther Brande, a citizen of the United States, residing at Garden City, Long Island, in the county of Nassau and State of New York, have invented a new, original, and ornamental Design for a Baby Bunting, of which the following is a full specification, reference being had to the accompanying drawing, forming a part thereof.

In the drawing:

Fig. 1 is a perspective view of a baby bunting, showing my new design;

Fig. 2 is a side elevational view; and

Fig. 3 is an end elevational view of the same.

Fig. 4 is a perspective view showing the baby bunting in folded position.

I claim:

The ornamental design for a baby bunting, as shown and described.

ESTHER BRANDE.
